BUILT-IN LAUNDRY HAMPER OR SIMILAR RECEPTACLE

Filed June 5, 1929 2 Sheets-Sheet 2

UNITED STATES PATENT OFFICE

ARTHUR J. FELTAULT, OF BLOOMFIELD, NEW JERSEY

BUILT-IN LAUNDRY HAMPER OR SIMILAR RECEPTACLE

Application filed June 5, 1929. Serial No. 368,477.

My present invention relates generally to receptacles, and has particular reference to a laundry hamper of unique character and construction.

5 A general object of my invention is to provide a laundry hamper of a character and construction which will render it peculiarly valuable in the type of modern residential apartments where the most efficient use of available space is highly desirable. More particularly, it is an object to provide a hamper adapted to be permanently associated with the wall of a bathroom or the like.

Briefly, my invention relates to a built-in receptacle constructed in a manner which 15 renders it peculiarly efficient for the purpose of accumulating laundry or the like for relatively short periods of time.

My improved built-in receptacle comprises 20 two complementary and separable sections, one of which is embedded in the bathroom wall and the other of which bulges outwardly into the room. One of the principal features of my invention lies in providing means for 25 permitting total withdrawal or removal of the outer or front section while at the same time retaining the same in position under normal conditions in a firm and reliable manner.

30 Another particular feature lies in so constructing the sections that the mutual assembly and disassociation thereof is a matter of extreme simplicity and one which is made possible by exceptionally simple and inexpensive structural expedients.

My improved laundry hamper is provided 35 with a feeding aperture to allow the insertion from time to time of the laundry which is to be accumulated, and a particular feature of 40 my invention lies in constructing the hamper in such a manner that the aperture is of the maximum possible size with respect to the general appearance and nature of the hamper as a whole.

45 Another general object of my invention is to provide the hamper of such a construction, and particularly the outer section thereof, that maximum roominess is attained with a minimum of possibly objectionable protrusion into the room itself. This I accomplish

by constructing the outer section with a main portion which conforms substantially to a segment of a vertical cylinder, and by providing the feeding aperture along an oblique plane with respect to such cylindrical surface. 55

Further features of my invention reside in the particular simple structural nature of the sections, the provision of efficient attaching portions, the provision of suitable ventilation openings, and in general, all those structural characteristics which render my device not only attractive in appearance and inexpensive to manufacture, but also simple to install and highly efficient in fulfilling its 60 contemplated functions. 65

For the attainment of the foregoing objects and such other objects as may hereinafter appear or be pointed out, I have constructed a device embodying the features of my invention and illustrated in the accompanying 70 drawings, wherein—

Figure 1 is a perspective view of a laundry hamper constructed in accordance with my present invention and shown in association with a wall of a bathroom; 75

Figure 2 is a side view partly in section showing the manner in which the hamper is associated with the bathroom wall;

Figure 3 is a cross-sectional view on an enlarged scale taken substantially along the 80 line 3—3 of Figure 1, with parts broken away for lack of space;

Figure 4 is a cross-sectional view on an enlarged scale taken substantially along the line 4—4 of Figure 1; 85

Figure 5 is a fragmentary cross-sectional view taken substantially along the line 5—5 of Figure 1; and

Figure 6 is a fragmentary cross-sectional view taken substantially along the line 6—6 90 of Figure 4.

Referring for the moment to Figure 2, I have shown for illustrative purposes a typical wall which includes within it the upright stud 10, which is one of a series to which suitable metal lath or the like is attached in the usual manner. Applied to the lath is the plaster 11 and over the latter are the tiles 12. The stud 10, and other suitably positioned studs, both vertical and horizontal, 95 100

serve to provide a structure somewhat in the nature of a frame for accommodating the embedded section of my device. Thus, I have shown by way of example a pair of screws or similar attaching devices 13 extending through one side wall of the embedded section into the upright stud 10.

The rear or embedded section of my device, most clearly illustrated in Figures 3 and 4, comprises the rear wall 14, the forwardly disposed side walls 15 and 16, the forwardly disposed top wall 17, and the forwardly disposed bottom wall 18. These several walls are caused to merge with each other in a smoothly curved manner so as to render the interior of the hamper totally devoid of any objectionable corners, angles, projections, and the like.

The entire section is preferably made of an integral piece of sheet metal, and in accordance with one feature of my invention, the forward edge portions of the sheet metal blank are bent outwardly to provide an outwardly disposed flange overlying the outer surface of the bathroom wall. Thus, in Figure 4, I draw attention to the side portions 19 and 20 of such outwardly disposed flange, the plane of the bathroom wall being designated by the reference numeral 21. It is to be noted that the flange portions 19 and 20 are formed by bending the sheet metal outwardly and then back on itself. Similarly, the top and bottom portions of this outwardly disposed flange are shown at 22 and 23 respectively in Figure 3.

For a purpose presently to be described in greater detail, the top portion of the flange is bent outwardly as at 24 so as to extend obliquely upwardly. The portion 24 provides an upturned projection which is substantially coextensive in length with the total width of the inner section, and which is spaced from and in front of the plane 21 of the bathroom wall. For a similar purpose, the forward portion of the bottom wall 18 is bent upwardly as at 25 to provide a similar upturned projection substantially coextensive in length with the width of the embedded section. It is to be noted, however, that the projection 25 lies rearwardly of the plane 21 of the bathroom wall.

The outer section of the laundry hamper consists similarly of a single element of sheet metal or the like, suitably enameled to suit requirements. It comprises the main portion 26 which conforms to a segmental portion of a vertical cylindrical surface, and a marginal portion 27 lying in a single plane parallel to the bathroom wall. The marginal portion 27 is adapted to overlie and thereby conceal the outwardly disposed flange of the embedded section. Thus, in Figure 4, it will be noted that the sides of the marginal portion 27 overlie the side portions 19 and 20; and in Figure 3, it will be seen that the top

and bottom portions of the marginal portion 27 overlie the top and bottom portions 22 and 23 of the outwardly disposed flange.

In accordance with my present improved construction, a rearwardly extending flange is carried at the edges of the marginal portion 27. This flange consists of the side portions 28 and 29 (Figure 4) and of the top portion 30 (Figure 3). A bottom portion, corresponding to the top portion 30, is omitted. This rearwardly extending flange is adapted to encircle the outwardly disposed flange upon the embedded section, thereby contributing to a more complete concealment of the latter and also serving to present an attractive outer appearance to the device as a whole. It is to be noted, however, that a slight clearance space 44 is provided between the rearwardly extending flange of the outer section and the outwardly disposed flange of the inner section, this clearance providing for additional permanent ventilation.

The bottom wall 31 of the outer section is substantially horizontal and is provided with the openings 32 for purposes of further ventilation.

To provide for removable association of the outer section with the embedded section, I provide a pair of lips at the top and bottom respectively of the outer section for removable engagement over the upturned projections 24 and 25 respectively of the embedded section. Thus, upon referring to Figure 3, it will be noted that an angular strip 33 is carried beneath the top portion 30 of the rearwardly extending flange, the strip 33 extending across the entire device and being inclined downwardly toward the rear. This provides a lip which engages over the projection 24 in the efficient manner shown. Similarly, a lip 34 is provided in the form of a suitably configured strip spot-welded or similarly associated with the bottom wall 31, the lip 34 engaging over the projection 25 in the efficient manner shown.

I prefer to provide a pair of hand grips or knobs 35 at the upper corners of the marginal portion 27 so that the entire front or outer section may be lifted clear of the embedded section and of the bathroom wall. To facilitate this separation, the lower ends of the sides 28 and 29 are attenuated or curved as shown at 36 in Figure 3.

To provide a feeding aperture of maximum feasible size, I terminate the upper edge of the body portion 26 at an oblique plane. This plane extends downwardly and forwardly from the upper portion of the device as a whole and the aperture 37 thus provided has a shape which is defined by the intersection with the cylindrical surface of the body portion 26 of the oblique plane referred to.

The closure for this aperture comprises a substantially flat element having a main por-

tion 38 and a rear portion 39. The upper edge of the latter is straight and substantially horizontal, and is hinged as at 40 to the top of the marginal portion 27. The rear portion 39 of the closure lies flush with the marginal portion 27, whereas the main portion 38 lies in the plane of the aperture 37. The portion 38 has a curved forward edge 41 which lies along the cylindrical surface, and this edge is preferably bent as shown most clearly at 42 in Figure 5 so as to provide a reinforcement in the nature of a bead.

Any suitable knob or handle such as that shown at 43, preferably of an ornamental character, is provided at the lower portion of the closure so that the latter may be lifted when desired to render the aperture 37 accessible. The bent construction of the closure and its manner of hinging is of considerable importance in that the accessible size of the aperture 37 is thereby greatly increased. Furthermore, when the closure is swung upwardly, its construction in the manner illustrated and described (viz., with the portions 38 and 39) allows the closure to be self-supporting in upright opened position, thereby leaving both hands free for the insertion of laundry.

The efficient nature of my device, not only from a manufacturing standpoint but also from the standpoint of installation and use, will be clear from the foregoing description. I draw particular attention to the fact that no part of the inner or embedded section is visible under normal conditions, and I attribute this advantageous result to the construction which provides the outwardly disposed flange on the embedded section and the rearwardly disposed flange on the outer section. The fact that only the outer section is visible allows the enamel or ornamentation thereof to be rendered uniform throughout and renders the particular ornamentation of the inner section, if any, relatively immaterial.

The provision of the upturned projections 24 and 25, and of the corresponding rearwardly extending lips on the outer section simplifies not only the manufacture of the device but also the use thereof. It is a comparatively simple matter to lift upwardly upon the knobs 35, thereby releasing the lips 33 and 34 and allowing the entire outer section to be lifted in its entirety clear of the wall so that accumulated laundry may be removed. It is an equally simple matter to lift the outer section by these same knobs, and to replace the same into its normal position. When so assembled, there is no likelihood whatever of the outer section coming loose, and an extremely pleasing and workmanlike appearance is presented.

The cylindrical configuration of the outer section is of importance because it provides

the maximum roominess without any objectionable bulging into the room; it also allows the ventilation openings 32 to be provided in a concealed position; and it renders it possible to provide a feeding aperture of maximum size and a closure of extreme simplicity.

It will of course be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. A laundry hamper comprising a pair of complementary separable sections one of which is adapted to be embedded in a wall of a room and the other of which is adapted to bulge outwardly into the room; said embedded section having a rear wall and forwardly disposed top, bottom, and side walls, the forward edge of said top wall having an upturned projection spaced from and in front of the plane of said wall; and said outer section being provided with a lip adapted to engage over said projection. 85

2. A laundry hamper comprising a pair of complementary separable sections one of which is adapted to be embedded in a wall of a room and the other of which is adapted to bulge outwardly into the room; said embedded section having a rear wall and forwardly disposed top, bottom, and side walls, the forward edge of said bottom wall having an upturned projection lying rearwardly of the plane of said wall; and said outer section being provided with a lip adapted to engage over said projection. 100

3. A laundry hamper comprising a pair of complementary separable sections one of which is adapted to be embedded in a wall of a room and the other of which is adapted to bulge outwardly into the room; said embedded section having a rear wall and forwardly disposed top, bottom, and side walls, the forward edges of said top and bottom walls having upturned projections which lie respectively in front of and behind the plane of said wall; and said outer section being provided with a pair of lips adapted to engage over said projections respectively. 115

4. A laundry hamper comprising a pair of complementary separable sections one of which is adapted to be embedded in a wall of a room and the other of which is adapted to bulge outwardly into the room; the forward edge of said embedded section having a pair of upturned projections at the top and bottom thereof respectively, the upper projection lying in front of and spaced from 125

said wall, and the lower projection lying rearwardly of said wall; and the outer section having a pair of rearwardly extending lips at the top and bottom thereof respectively for removable engagement over said projections respectively.

5. A laundry hamper comprising a pair of complementary separable sections one of which is adapted to be embedded in a wall of a room and the other of which is adapted to bulge outwardly into the room; the forward edge of said embedded section having a pair of upturned projections at the top and bottom thereof respectively, the upper projection lying in front of and spaced from said wall, and the lower projection lying rearwardly of said wall; each of said projections being substantially coextensive in length with the width of said embedded section; and the outer section having a pair of rearwardly and downwardly extending lips adapted to be removably engaged over said projections respectively.

6. A laundry hamper comprising a pair of complementary separable sections one of which is adapted to be embedded in a wall of a room and comprises a rear wall and forwardly disposed top, bottom, and side walls, the forward edge of said embedded section carrying an outwardly disposed flange adapted to overlie the outer surface of said wall; the other section being adapted to bulge outwardly into said room and carrying at its edge a rearwardly extending flange adapted to encircle said outwardly disposed flange.

7. A laundry hamper comprising a pair of complementary separable sections one of which is adapted to be embedded in a wall of a room and comprises a rear wall and forwardly disposed top, bottom, and side walls, the forward edge of said embedded section carrying an outward disposed flange adapted to overlie the outer surface of the said wall and having its upper portion spaced forwardly from said wall; the outer section being adapted to bulge into the room and carrying at its edge a rearwardly extending flange adapted to encircle said outwardly disposed flange; and a lip carried by said outer section and engageable over said upper portion of the outwardly disposed flange.

8. A laundry hamper comprising a pair of complementary separable sections one of which is adapted to be embedded in a wall of a room and comprises a rear wall and forwardly disposed top, bottom, and side walls, the forward edge of said embedded section carrying an outwardly disposed flange adapted to overlie the outer surface of said wall; the other section being adapted to bulge outwardly into the room and comprising a plane marginal portion substantially parallel to said wall and adapted to overlie and conceal said outwardly disposed

flange, the edge of said marginal portion carrying a rearwardly extending flange which encircles said outwardly disposed flange.

9. A laundry hamper comprising a pair of complementary separable sections one of which is adapted to be embedded in a wall of a room and comprises a rear wall and forwardly disposed top, bottom, and side walls, the forward edge of said embedded section carrying an outwardly disposed flange adapted to overlie the outer surface of said wall; the other section being adapted to bulge outwardly into the room and carrying at its edge a rearwardly extending flange adapted to encircle said outwardly disposed flange; said rearwardly extending flange comprising a top portion and two side portions, the side portions being attenuated at their lower ends.

10. A laundry hamper comprising a pair of complementary separable sections one of which is adapted to be embedded in a wall of a room and comprises a rear wall and forwardly disposed top, bottom, and side walls, the forward edge of said embedded section carrying an outwardly disposed flange adapted to overlie the outer surface of said wall; the other section being adapted to bulge outwardly into the room and comprising a plane marginal portion substantially parallel to said wall and adapted to overlie and conceal said outwardly disposed flange, an oblique feeding aperture in said outer section, and a closure for said aperture and hinged to said marginal portion, said closure comprising a portion parallel to said marginal portion and a main portion oblique thereto.

11. A laundry hamper comprising a pair of complementary separable sections one of which is adapted to be embedded in a wall of a room and the other of which is adapted to bulge outwardly into the room, the latter section comprising a main portion which conforms to a segment of a vertical cylindrical surface, and a marginal portion lying in a single plane parallel to said wall; said outer section being provided with a feeding aperture defined by the intersection with said cylindrical surface of an oblique plane; and a closure for said aperture comprising a main portion overlying said aperture and a rear portion hinged to said marginal portion and parallel thereto.

In witness whereof I have signed and sealed this specification this 24th day of May, 1929.

ARTHUR J. FELTAULT.
